ELECTRON DISCHARGE DEVICE

Jesse L. Worden, Chicago, Ill., assignor to General Electric X-Ray Corporation, Chicago, Ill., a corporation of New York

Application October 29, 1931, Serial No. 571,701

11 Claims. (Cl. 250—35)

The present invention relates to thermonic devices and as illustrated has to do with an X-ray tube having a water cooled anode.

Heretofore such tubes, when the anode has been cooled by water, have been subjected at times to an irregular bumping effect. This bumping is believed to be due to the generation of steam at the back of the hollow head of the anode.

The water which is in direct contact with the internal wall of the copper anode head is converted into steam forming a small pocket. The formation of this pocket permits no water to come into contact with the adjacent anode wall for a short interval of time. During such short interval of time, however, that portion of the anode head not in contact with water becomes highly heated and to the extent that when finally water does come in contact with the anode wall it is converted into steam at the rate amounting to that of a miniature explosion. The explosive force of the steam so generated pushes water out of the anode head at a high velocity, reacting with an equal and opposite force to the head of the anode. Thus, there is produced and transmitted to the whole tube a bumping effect.

The object of the present invention is to provide means for preventing such bumping, and contemplates a baffle arrangement within the water chamber of the anode to disperse the force of any generation of steam in the anode and to impede violent movement of liquid therein, and to concurrently guide the flow of cooling water so as not to lessen the volume of such flow to the head of the anode. Where anode is used hereinbefore, any cooled electrode or other part is intended to be included.

Other objects of the invention as appear hereinafter reside in the novel construction, unique combination, and improved arrangement of the elements set forth in the following description.

With reference to the accompanying drawing hereby made a part of this description and where one form of the invention is illustrated, and in which like reference characters refer to the same parts:

Figure 1 is a plan view of one form of X-ray tube with a schematic diagram of its connections;

Figure 2 is an enlarged longitudinal sectional view of the anode of the tube shown in Figure 1;

Figure 3 is an enlarged plan view of one form of a baffle plate as is used within the anode; and

Figure 4 is an enlarged plan view of another

form of baffle plate which may be used within the anode.

Referring now to Figures 1, 2 and 3, it will be noted that the anode 1 is supplied with cooling water or other cooling media which flows from a reservoir 2 into a cavity 3 in anode head 4. Secured to and at the back end of hollow anode 1 is a collar 5 having threads 6.

A twisted metal rod 7 supports flat metal baffles 8 which approximate the shape of a third circle. These are mounted upon rod 7 in the following manner. Each baffle 8 has an extension 9 through which there is an aperture 10. The aperture 10 is of the same contour as the periphery of rod 7 at the point of attachment. As illustrated in Figure 2, baffles 8 lie in planes normal to the axis of the anode and are spaced upon twisted metal rod 7 at intervals and to effect by a staggered arrangement a progressive rotative distribution about said rod 7 at angles of one hundred and twenty degrees. In other words, every third baffle 8 radiates from the rod 7 in the same radial direction.

Centrally located in a round metal closure plate 11 for anode 1 is a hub 12 having a rectangular aperture 13 of a cross section suitable to tightly secure the end 14 of rod 7.

Plate 11 rests against collar 5 for bearing surface to support rod 7 and the attached baffles 8 in the cavity 3 of anode 1.

Nipple 15 of reservoir 2 may have an integral flange 16 disposed to abut flatly against plate 11 when drawn and held thereto by a cap 17 which has threads 18 thereon to engage with threads 6 of collar 5. Intermediate the reservoir and hollow anode chamber there is thus provided a water tight joint suitable to maintain a plurality of baffles and supporting rod within said hollow anode.

Figure 4 illustrates another form which the baffle may take. Baffle action is obtained by means of a coarse screw like arrangement similar in shape to a screw conveyor having very deep thread depth 8a, as compared with the root diameter 7a. This baffle unit may be made in any desired fashion, preferably by either sand or die casting. The method of use and its attachment to the tube is similar to that described before except that it is preferred that the baffle be attached to the plate 11a by means of a screw 13a which passes through hole 12a and engages a threaded hole in the end 14a of the baffle.

The baffles 8 and 8a by the arrangement shown resist an extended longitudinal movement of the cooling water in the chamber 3 in either direc-

tion. An explosive generation of steam at face 19 of head 4 will exert a longitudinal force in the hollow chamber of the anode. The water forced back by such explosive force will be divided at the first baffle 8 or 8a and a part of the explosive force there absorbed. At the second baffle 8 or 8a, there will be a further division, and at the third a still further division. Thus the force of the explosion will be distributed in fractional parts and at spaced time intervals instead of in a single blow carrying the full force of the initial explosion. The explosive force will thus be nullified and made negligible. The explosive disturbance being nullified in the manner indicated, the explosion does not produce a physical movement of the anode or of the tube of any disturbing consequence.

When there are no baffles in the chamber 3, an explosion at face 19 results in a movement of the cooling material in the anode in one direction and a prompt recoil in the opposite direction with a resulting objectionable jarring or bumping of the tube, all of which is obviated by the structure herein described.

I claim:

25. 1. In a vacuum tube, an electrode having a chamber to receive a cooling medium, a reservoir communicating with said chamber, and baffle means extending longitudinally of said chamber and displacing such medium from a relatively large central portion of said chamber, the medium being vaporized at one end of said chamber by the heat of said electrode and being impulsively urged toward said reservoir, the baffle means directing the urged medium over a tortuous course along the sides of said chamber.

2. In a vacuum tube, an electrode having a hollow chamber to receive a cooling medium, a reservoir connected to said electrode for the circulation of such medium between said reservoir and said chamber, baffle means directing the medium to follow a tortuous course generally longitudinally of said chamber as it moves therein, the medium being intermittently and explosively vaporized at one end of said chamber by the heat of the electrode whereby said medium is impulsively urged toward said reservoir, said baffle means occupying a central position in said chamber for dispersing the flow of the impulsively urged medium and directing it along the walls of said chamber.

3. In a vacuum tube, an electrode having a hollow chamber for a cooling medium, a reservoir for the cooling liquid charging said chamber, and means disposed within and centrally of said chamber for directing the flow of the medium along the interior walls thereof and precluding the flow of such medium longitudinally and centrally of said chamber.

4. In an electrode having a hollow chamber receiving a circulatory cooling medium, a baffle member extending longitudinally of said chamber and of slightly smaller transverse dimensions than said chamber, said baffle member being disposed centrally of said chamber and having portions extending radially thereof for impeding the flow of such medium longitudinally of said chamber except at a transverse section substantially along such walls.

5. In an electrode comprising a body having a hollow chamber to receive a cooling medium for movement longitudinally thereof, a helical baffle member extending centrally and longitudinally of said chamber to impede the movement of such medium liquid through the greater portion of

the transverse section of the chamber, said portion being central of said section.

6. In a vacuum tube, an electrode with an end subjected to heat and having a chamber for a cooling medium, said chamber extending inwardly of said electrode to adjacent such heated end, a cooling medium, a reservoir for such cooling medium at the other end of said electrode, gravity causing the cooling medium to flow toward the heated end of said electrode to there be vaporized, the path of flow of such vapor in said chamber being opposed to the gravitational flow of the cooling medium, and a baffle axially disposed in said chamber and having a radial projection in the normal path of the opposed vapor and cooling medium movements for arresting direct substantially linear movement longitudinally of said electrode of globules of the vapor and any cooling medium enclosing said globules or moved therewith.

7. In a vacuum tube, an electrode with an end subjected to heat and having a chamber for a cooling medium, said chamber extending inwardly of said electrode to adjacent such heated end, a cooling medium, a reservoir for such cooling medium at the other end of said electrode, gravity causing the cooling medium to flow toward the heated end of said electrode to there be vaporized, the path of flow of such vapor in said chamber being opposed to the gravitational flow of the cooling medium, and a symmetrically arranged baffle member disposed centrally of said chamber elongating the path of movement of globules of such vapor and cooling medium surrounding such globules longitudinally of said electrode.

8. In a vacuum tube, an electrode with an end subjected to heat and having a chamber for a cooling medium, said chamber extending inwardly of said electrode to adjacent such heated end, a cooling medium, a reservoir for such cooling medium at the other end of said electrode, gravity causing the cooling medium to flow toward the heated end of said electrode to there be vaporized, the path of flow of such vapor in said chamber being opposed to the gravitational flow of the cooling medium, and a continuous helical wall axially and centrally traversing the chamber in said electrode and providing a tortuous passageway substantially co-extensive with said electrode for retarding the movement of the globules of such vapor and the cooling medium enclosing such globules and set in motion thereby, the longitudinal spacing between adjacent sections of said wall being relatively slight to prevent direct linear movement of such vapor globules and enclosing cooling medium longitudinally of said electrode in a straight line.

9. In a vacuum tube, an electrode with an end subjected to heat and having a chamber for a cooling medium, said chamber extending inwardly of said electrode to adjacent such heated end, a cooling medium, a reservoir for such cooling medium at the other end of said electrode, gravity causing the cooling medium to flow toward the heated end of said electrode to there be vaporized, the path of flow of such vapor in said chamber being opposed to the gravitational flow of the cooling medium, and a baffle member having parts spaced from one another axially of said electrode and extending transversely from a central position in said chamber for directing globules of such vapor as formed incident to the heating of said medium and the cooling medium enclosing such globules.

and moving therewith along a tortuous and elongated path through said electrode to said reservoir whereby to prevent extended direct and unbroken linear movement of such globules longitudinally out of said electrode at high speed and into the said reservoir.

5 10. In an X-ray tube, an anode comprising a body having a chamber, a rod disposed longitudinally of said chamber, and baffle plates at

intervals on said rod and extending transversely of said chamber.

11. In an X-ray tube, an anode comprising a body having a chamber, and segmental baffle plates in said chamber, said plates being radial of said chamber and in spaced relation axially thereof.
